DRAFT REGULATOR

Arthur D. Cole, Minneapolis, Minn.

Application October 19, 1938, Serial No. 235,807

13 Claims. (Cl. 236—45)

My invention relates to draft regulators and has for an object to provide an extremely compact structure by means of which the draft in chimneys may be automatically regulated.

Another object of the invention resides in providing a construction having a minimum number of moving parts.

A feature of the invention resides in providing a draft regulator in which the friction of the moving parts is a minimum.

An object of the invention resides in providing a draft regulator utilizing a damper having oppositely extending parts arranged so that the pressure moment of each part is substantially the same whereby the deposit of soot upon the damper does not destroy the balance of the moving parts.

Another object of the invention resides in providing a case having a passageway therein and in providing a wall structure within the case forming a vane chamber and in providing a shaft having both a damper and a vane thereon, the vane being disposed within said vane chamber.

Another object of the invention resides in constructing the vane housing shorter than the transverse dimension of the case to leave unobstructed portions of the passageway situated adjacent the wall structure forming the vane chamber and in constructing the damper with parts disposed within said portions of the passageway.

Another object of the invention resides in providing a neat and compact structure adapted to occupy a minimum amount of space and to be readily connected in the smoke pipe of a heating plant.

A feature of the invention resides in providing the construction which does not project appreciably beyond the confines of the smoke pipe.

Other objects of the invention reside in the novel combination and arrangement of parts and in the details of construction hereinafter illustrated and/or described.

In the drawings:

Fig. 1 is a perspective view of a draft regulator illustrating an embodiment of my invention and with parts cut away to show the interior construction of the same.

Fig. 2 is a longitudinal sectional view taken on line 2—2 of Fig. 1.

Fig. 3 is a cross sectional view taken on line 3—3 of Fig. 2.

Fig. 4 is an elevational view of the structure shown in Fig. 1 with a portion of the same broken away to illustrate the interior construction of the invention.

Fig. 5 is an inverted plan view taken on line 5—5 of Fig. 3.

My invention comprises a case which I have indicated in its entirety by the reference character A and which is constructed from sheet metal. This case is made in two parts designated by the reference numerals 10 and 11. The part 11 is constructed from a blank which is bent to form a rounded bottom 12 and two spaced parallel side walls 13 and 14. The part 10 is constructed to provide a top 15 which is raised at the center as indicated at 16. The raised portion 16 is arcuate in form and is connected by short crescent-shaped walls 17 to the top proper 15. The part 10 is further formed with end walls 18 and 19 which are constructed with semi-circular openings 21 concentric with the curved bottom 12 of the case.

The part 10 of case A is connected to the part 11 as follows: formed along the upper edges of the side walls 13 and 14 and along the ends of the said walls are outwardly extending flanges 22. On the corresponding edges of the part 10 are lips 23 which are turned over the said flanges and which are clinched thereon to hold the structure firmly assembled.

By means of the construction of the case A a passageway 24 is formed therein. The opening formed by the free end of the rounded bottom 12 and the opening 21, at one end of the case, forms an inlet to the passageway 24 and is indicated by the reference numeral 25. A similar construction at the other end of the case is designated by the reference numeral 26 and forms an outlet to said passageway.

For connecting the draft regulator to the smoke pipe of a heating plant the following construction is employed. The length of the part 11 of the case A, forming the bottom 12 is considerably longer than the portion of the case disposed between the end walls 18 and 19 to provide semi-circular extensions 27, projecting therebeyond. Attached to the end walls 18 and 19 are semi-circular rings 28 which, together with the extensions 27, form nipples adapted to be telescoped with respect to the ends of the pipe between which the draft regulator is to be mounted.

Extending transversely of the case A and the side walls 13 and 14 is a shaft 29. This shaft is journaled in bearings formed by drilling holes in the said side walls. The arcuate portion 16 of the top 15 is so constructed that the axis of the same substantially coincides with the axis of the shaft 29, for a purpose to be presently more fully described.

Within the interior of the case A is provided a wall structure, indicated in its entirety by the reference numeral 31. This wall structure consists of two converging walls 32 and 33 and two sector-shaped parallel walls 34 and 35. The wall 33 is connected to the end wall 19 at the juncture of the ring 23 therewith and extends toward the axis of the shaft 29. The wall 32 is similarly constructed and is connected to the end wall 18 at a similar locality. Both of these walls fall short of one another at the converging ends to leave a space 36 therebetween. The two walls 34 and 35, in addition to being parallel to one another, are parallel to the side walls 13 and 14 of case A and are spaced from one another and from said side walls to form in conjunction with the walls 32 and 33 and the various walls of the case a chamber 37 within the wall structure 31 and to leave unobstructed portions of the passageway 24 indicated at 38 and 39 which are disposed between said wall structure and the side walls 13 and 14. The sector-shaped walls 34 and 35 are connected at their edges to the crescent-shaped walls 17 and extend up to the arcuate portion 16 of the top 15.

In the wall 32 are formed louvers 41 which provide openings 42 which bring the chamber 37 into communication with the passageway 24 at the inlet end of the draft regulator. In the upper portion of the end wall 19 are provided openings 43 which bring the said chamber in communication with the atmosphere at the discharge end of the draft regulator.

Attached to the shaft 29 is a damper 40 which has a semi-circular part 44 which fits loosely within the portion 30 of passageway 24 of case A opposite the wall structure 31 and which conforms to the shape of the rounded bottom 12 of the case A when the damper is in vertical position. In addition this damper is constructed with two other rectangular-shaped parts 45 and 46 which extend up into the two portions 38 and 39 of the passageway 24 and which conform to the shape of the said passageway lying close to the walls 13, 34, 35 and 14. The part 44 of damper 40 issues from one side of the shaft 29 and the parts 45 and 46 issue in the opposite direction and from the other side of the shaft. If desired, the damper parts 45 and 46 may be made integral with the damper part 44.

Within the vane chamber 37 is disposed a vane 47. This vane may be made integral with the damper 40 or as a separate structure, if desired. In the drawings the said vane is shown as a separate plate which is constructed with a groove 48 adapted to receive the shaft 29. Shaft 29 and groove 48 are constructed with off-sets 49 which prevent rotation of the shaft with respect to the plate. The portion of the plate 47 in which the groove 48 is formed overlies the damper 40 and is spot welded or riveted thereto. By means of this construction the shaft 29 is fixedly secured to damper 40 and the vane 47 and is also held from longitudinal or rotational movement with reference thereto.

The vane 47 fits snugly between the walls 34 and 35 of the wall structure 31 and the end of said vane travels in close proximity to the arcuate portion 16 of the top 15. It will be noted that the vane 47 divides the chamber 37 into two compartments, one being in communication with the atmosphere through the openings 43 and the other in communication with the passageways 24, 38 and 39 through the openings 42. The two damper parts 45 and 46 lie in the same plane as

the damper part 44 and together have a pressure moment substantially equal to the pressure moment of the damper part 44. By so constructing the draft regulator the deposit of soot upon the damper does not destroy the balance and interfere with the operation of the device. The vane 47 extends angularly from the plane of the damper 40 so that, when the damper 40 projects transversely of the passageways 24, 38 and 39, the said vane is disposed at one end of its path of movement within the chamber 37 and so that, when the damper lies longitudinally with respect to the said passageways, the vane 47 is disposed at the other end of its path of movement within the chamber 37.

Attached to one end of the shaft 29 is an arm 51. This arm has secured to it a counter-weight 52. Shaft 29 and the arm 51 and counter-weight 52 may be made of one piece of wire which is bent in the desired manner, the weight 52 being constructed by forming convolutions at the end of the said piece of wire. The other end of the shaft 29 has secured to it a sheave 53. This sheave may be of any suitable construction and has attached to it a chain 54. Chain 54 carries an adjustable counter-weight 55 consisting of a number of washers 56 attached to a cotter key 57 which in turn is secured to the end of the chain 54. The sheave 53 is shown as being segmental in form and of the circumferential extent of a semi-circle. This sheave is adapted to engage two stops 58 and 59 formed on a stamping 61 which is mounted on the wall 14 of case A. These stops limit the positions of the dampers 40 to transverse and longitudinal.

The operation of the invention is as follows: In normal position, the vane 47 is to the right as viewed in Fig. 2 and the damper lies longitudinally with respect to the passageway 24. As the draft in the chimney increases, suction is created in the chamber 37 to the left of the vane 47 and the said vane is gradually moved toward the left. As the vane so moves, the damper is swung into restraining position and the amount of gas passing by the damper is reduced. This reduces the suction tending to move vane 47 to the left and a balance is reached which permits a certain amount of gas to pass through the regulator in a given time. As the draft in the chimney varies, the suction on the vane 47 correspondingly varies and the degree of opening and closing of the damper is controlled accordingly. In this manner the flow of gas through the draft regulator may be maintained substantially uniform. By adjusting the number of washers of weight 55 any degree of draft can be maintained in the smoke pipe with which the draft regulator is connected.

The advantages of my invention are manifest. An extremely compact structure is provided. The draft regulator may be constructed at an extremely low cost. The device operates with a minimum amount of friction. There being but one shaft and one moving unit, the device is not apt to get out of order and will function indefinitely without attention. Due to the arranging of one-half of the damper on one side of the shaft and the other one-half on the other side of the shaft, accumulation of soot on the damper parts does not affect the operation of the invention. The device operates without removal of air from the room in which it is installed. The draft regulator is fairly short and projects a minimum amount beyond the confines of the pipe with which it is associated so that the regulator may be installed in crowded quarters.

Changes in the specific form of my invention, as herein disclosed, may be made within the scope of what is claimed without departing from the spirit of my invention.

Having described my invention, what I claim as new and desire to protect by Letters Patent is:

1. A draft regulator comprising a case constructed with side walls and having a passageway therethrough, a shaft extending transversely of said side walls and disposed within said case, a wall structure forming a sector-cylindrical shaped chamber within said case with its vertex substantially at the axis of said shaft and spaced from said side walls to leave unobstructed, portions of said passageway between said wall structure and the side walls of the case, a damper in said passageway having a part issuing from one side of said shaft, and other parts disposed in the portion of the passageway between said wall structure and side walls and issuing from the other side of said shaft, said second named damper parts being disposed so that the pressure moment thereof opposes the pressure moment of said first named damper part, a vane issuing from said shaft and disposed within said chamber between said second named damper parts, said chamber being in communication with the atmosphere on one side of the vane and in communication with said passageway on the other side of said vane, said damper and vane being fixed relative to one another and said damper and vane being angularly disposed so that movement of the vane from normal position to operative position moves the damper from open to obstructing position, and a counterweight carried by the shaft to balance the vane.

2. A draft regulator comprising a case constructed with side walls and a top having an arcuate portion, said case having a passageway therethrough, a shaft extending transversely of said side walls and disposed within said case, two converging walls within said case connected to the top at the arcuate portion thereof and approaching one another substantially at the axis of said shaft, sector-cylindrical shaped walls connected with said converging walls to form a sector-cylindrical shaped chamber within said walls, said sector shaped walls being spaced from said side walls to leave unobstructed, portions of said passageway between said sector shaped walls and the side walls of the case, a damper in said passageway having a part issuing from one side of said shaft, and other parts disposed in the portion of the passageway between said wall structure and side walls and issuing from the other side of said shaft, said second named damper parts being disposed so that the pressure moment thereof opposes the pressure moment of said first named damper part, a vane issuing from said shaft and disposed within said chamber and between said last named damper parts, said chamber being in communication with the atmosphere on one side of the vane and in communication with said passageway on the other side of said vane, said damper and vane being fixed relative to one another and said damper and vane being angularly disposed so that movement of the vane from normal position to operative position moves the damper from open to obstructing position, and a counterweight carried by the shaft to balance the vane.

3. A draft regulator comprising a case constructed with side walls and having a passageway therethrough, a shaft extending transversely of said side walls and disposed within said case, a

wall structure comprising two walls parallel with said side walls and spaced from one another and from said side walls, means forming in conjunction with said two parallel walls a chamber therebetween having an arcuate surface concentric with said shaft, said parallel walls leaving unobstructed, portions of the passageway between said parallel walls and the side walls of the case, a damper in said passageway having a part issuing from one side of said shaft and other parts in said denoted portions of the passageway issuing from the other side of said shaft, said second named damper parts being disposed so that the pressure moment thereof opposes the pressure moment of said first named damper part, a vane issuing from said shaft and disposed within said chamber, said vane traveling along said arcuate surface and adjacent said parallel walls, said chamber being in communication with the atmosphere on one side of the vane and in communication with said passageway on the other side of said vane, said damper and vane being fixed relative to one another and said damper and vane being angularly disposed so that movement of the vane from normal position to operative position moves the damper from open to obstructing position, and a counterweight carried by the shaft to balance the vane.

4. A draft regulator comprising a case constructed with side walls and a top having an arcuate portion at the center of the same, said case having a passageway therethrough, a shaft extending transversely of said side walls and disposed within said case at the axis of said arcuate portion, a pair of sector shaped parallel walls connected to said arcuate portion and having their vertexes disposed substantially at the axis of said shaft, a pair of converging walls connected to the edges of said parallel walls, said parallel walls and converging walls forming with the top of said case a sector-cylindrical chamber, a damper in said passageway having a part issuing from one side of said shaft, and other parts issuing from the other side of said shaft and disposed between said side walls and said parallel walls, said second named damper parts being disposed so that the pressure moment thereof opposes the pressure moment of said first named damper part, a vane issuing from said shaft and disposed within said chamber, said vane following along the arcuate portion of the case and along the parallel walls, said chamber being in communication with the atmosphere on one side of the vane and one of said converging walls being provided with an opening for bringing said chamber on the other side of said vane in communication with said passageway, said damper and vane being fixed relative to one another and said damper and vane being angularly disposed so that movement of the vane from normal position to operative position moves the damper from open to obstructing position, and a counterweight carried by the shaft to balance the vane.

5. A draft regulator comprising a case constructed with side walls, end walls and a top having an arcuate portion in the center of the same, said case having a passageway therein, a shaft extending transversely of said side walls and disposed within said case substantially at the axis of the arcuate portion of the top thereof, two parallel sector shaped walls connected with the arcuate portion of said top and having their vertexes substantially at the axis of said shaft and spaced from the side walls, two converging walls connected to the end walls of said case and to

said sector shaped walls and forming with said sector shaped walls and the top of the case a sector-cylindrical shaped chamber, a damper in said passageway having a part issuing from one side of said shaft and other parts issuing from the other side of said shaft and disposed between said side walls and said parallel walls, said second named damper parts being disposed so that the pressure moment thereof opposes the pressure moment of said first named damper part, a vane issuing from said shaft and disposed within said chamber, said vane following along the arcuate portion of the case and along the parallel walls, one of said converging walls having an opening therein for bringing said chamber on one side of said vane into communication with said passageway, the end wall of the case opposite said denoted converging wall having an opening therein outwardly of the walls of the case defining said passageway and disposed within the confines of said parallel walls for bringing said chamber into communication with the atmosphere on the other side of said vane, said damper and vane being fixed relative to one another and said damper and vane being angularly disposed so that movement of the vane from normal position to operative position moves the damper from open to obstructing position, and a counterweight carried by the shaft to balance the vane.

6. A draft regulator comprising a case constructed from sheet metal and including a blank formed to provide a rounded bottom and two parallel side walls connected therewith, and a second blank formed to provide a top having an arcuate portion and end walls connected with said side walls, a shaft extending transversely of said side walls, a wall structure within said case forming in conjunction with the arcuate portion of said top a sector-shaped chamber having its vertex substantially at the axis of said shaft, a damper within said case carried by said shaft and disposed exteriorly of said chamber, a vane within said chamber and carried by said shaft, said damper and vane being fixed relative to one another and said damper and vane being angularly disposed so that movement of the vane from normal position to operative position moves the damper from open to obstructing position, and a counterweight carried by the shaft to balance the vane.

7. A draft regulator comprising a case constructed from sheet metal and including a blank formed to provide a rounded bottom and two parallel side walls connected therewith, and a second blank formed to provide a top having an arcuate portion and end walls connected with said side walls, a shaft extending transversely of said side walls, a wall structure within said case forming in conjunction with said arcuate top a sector shaped wall having its vertex substantially at the axis of said shaft, a damper within said case carried by said shaft and disposed exteriorly of said chamber, a vane within said chamber and carried by said shaft and a nipple formed partly by said curved bottom and partly by a part carried by said end wall, said damper and vane being fixed relative to one another and said damper and vane being angularly disposed so that movement of the vane from normal position to operative position moves the damper from open to obstructing position, and a counterweight carried by the shaft to balance the vane.

8. A draft regulator comprising a case having a passageway therethrough, a shaft in said case extending transversely of said passageway, a

damper on said shaft having two spaced parts and situated within said passageway, a wall structure disposed between said damper parts and providing a vane chamber communicating with the exterior at one locality and with said passageway at another locality, a vane on said shaft disposed between the damper parts and within said vane chamber and subject to atmospheric pressure on one side and flue gas pressure on the other side, said damper and vane being fixed relative to one another and said damper and vane being angularly disposed so that movement of the vane from normal position to operative position moves the damper from open to obstructing position, and a counterweight carried by the shaft to balance the vane.

9. A draft regulator comprising a case constructed with side walls and having a straight passageway therethrough, a shaft extending transversely of said side walls and arranged with its axis substantially at right angles to the direction of extent of said passageway and disposed within said case, a wall structure forming a sector-cylindrical shaped chamber within said case with its vertex substantially at the axis of said shaft, said chamber being symmetrical with reference to a plane through the axis of said shaft and transverse of the axis of said passageway, a damper in said passageway carried by said shaft, a vane in said sector shaped chamber issuing from said shaft, said chamber being in communication with the atmosphere on one side of the vane and in communication with said passageway on the other side of said vane, said damper and vane being fixed relative to one another and said damper and vane being angularly disposed so that movement of the vane from normal position to operative position moves the damper from open to obstructing position, and a counterweight carried by the shaft to balance the vane.

10. A draft regulator comprising a case constructed with spaced parallel side walls, a top and a bottom connecting the same and forming therewith a passageway, said bottom and top being constructed to make the passageway semi-circular in cross section at the lower portion of the same and rectangular in cross section at the upper portion of the same, a pair of walls disposed within the case and parallel with said side walls, converging walls connected thereto, said second named parallel walls and converging walls forming within the case a chamber of rectangular cross section disposed in the rectangular portion of the passageway, a shaft extending transversely of the side walls and having its axis disposed substantially at the locality of convergence of said converging walls, a damper having a semi-circular part issuing from said shaft on one side thereof and disposed in the semi-circular portion of said passageway, said damper having a pair of rectangular-shaped parts extending from said shaft on the opposite side thereof and disposed within the rectangular portion of said passageway, said second named damper parts being disposed so that the pressure moment thereof opposes the pressure moment of said semi-circular damper part, a vane issuing from said shaft and disposed within said chamber between said second named damper parts, said chamber being in communication with the atmosphere on one side of the vane and in communication with said passageway on the other side of said vane, said damper and vane being fixed relative to one another and

said damper and vane being angularly disposed so that movement of the vane from normal position to operative position moves the damper from open to obstructing position, and a counterweight carried by the shaft to balance the vane.

11. A draft regulator comprising a case constructed with spaced parallel side walls, a top and a bottom connecting the same and forming therein a passageway, said bottom and top being constructed to make the passageway semi-circular in cross section at the lower portion of the same and rectangular in cross section at the upper portion of the same, a pair of parallel walls disposed within the case and parallel with said side walls, converging walls connected thereto, said second named parallel walls and converging walls forming within the case a chamber of rectangular cross section disposed in the rectangular portion of the passageway, a shaft extending transversely of the side walls and having its axis disposed substantially at the locality of convergence of said converging walls, a damper having a semi-circular part issuing from said shaft on one side thereof and disposed in the semi-circular portion of said passageway, said damper having a pair of rectangular-shaped parts extending from said shaft on the opposite side thereof and disposed within the rectangular portion of said passageway, said second named damper parts being disposed so that the pressure moment thereof opposes the pressure moment of said semi-circular damper part, a vane issuing from said shaft and disposed within said chamber between said second named damper parts, said chamber being in communication with the atmosphere on one side of the vane and in communication with said passageway on the other side of said vane, said damper and vane being fixed relative to one another and said damper and vane being angularly disposed so that movement of the vane from normal position to operative position moves the damper from open to obstructing position, the distance from said shaft to the outermost portion of said top of the case being greater than the distance between the shaft and the lowermost portion of the case to give sufficient length to the second named damper parts to cause the moment thereof to balance the moment of the first named damper parts, and a counterweight carried by the shaft to balance the vane.

12. A draft regulator comprising a case constructed with side walls and having a passageway therethrough, a shaft extending transversely of said side walls and disposed within said case, a wall structure forming a sector-cylindrical shaped chamber within said case with its vertex substantially at the axis of said shaft and spaced

from said side walls to leave unobstructed, portions of the passageway between said wall structure and the side walls of the case, a damper in said passageway having a part issuing from one side of said shaft, and other parts disposed in the portions of the passageway between said wall structure and side walls and issuing from the other side of said shaft, said second named damper parts being disposed so that the pressure moment thereof opposes the pressure moment of said first named damper part, a vane issuing from said shaft and disposed within said chamber between said second named damper parts, said chamber being in communication with the atmosphere on one side of the vane and in communication with said passageway on the other side of said vane, said damper and vane being fixed relative to one another and said damper and vane being angularly disposed so that movement of the vane from normal position to operative positions moves the damper from open to obstructing position, the combined longitudinal extent of said second named damper parts and vane being substantially equal to the longitudinal extent of said first named damper part, and a counterweight carried by the shaft to balance the vane.

13. In combination, a case providing a passageway for flue gases, a wall structure forming a sector-cylindrical shaped chamber of shorter length than the transverse dimension of the case projecting into the passageway with its vertex crosswise thereof and spaced from the case, said chamber communicating with the passageway at one radial surface and with the atmosphere at the other radial surface, a shaft extending transversely of the passageway at the vertex of the chamber, a vane carried by the shaft and oscillable within the chamber about the vertex thereof, a damper carried by the shaft at a fixed angle with respect to the vane and having a part disposed in the portion of the passageway on the side of the shaft opposite the chamber and having two parts disposed in the portions of the passageway situated on the other side of the shaft and between the chamber and case, said second named parts being constructed so that the pressure moment thereon opposes the pressure moment on the first named part of said damper, a counterweight carried by the shaft to balance the weight of the vane, said damper and vane being fixed relative to one another and said dampers and vane being angularly disposed so that movement of the vane from normal position to operative position moves the damper from open to obstructing position.

ARTHUR D. COLE.
